UNITED STATES PATENT OFFICE.

ISAÏE FRÉCHETTE, OF MONTREAL, CANADA.

ANVIL FOR PEGGING-MACHINES.

SPECIFICATION forming part of Letters Patent No. 685,398, dated October 29, 1901.

Application filed March 8, 1901. Serial No. 50,335. (No model.)

To all whom it may concern:

Be it known that I, ISAÏE FRÉCHETTE, a subject of the King of Great Britain, residing at Montreal, in the Province of Quebec and Dominion of Canada, have invented new and useful Improvements in Anvils for Pegging-Machines, of which the following is a specification.

The object of this invention is to provide 10 an anvil for pegging-machines which shall overcome the tendency of anvils as at present constructed to rough up or wrinkle the inner sole of the shoe during the feeding of said shoe upon the horn, and, furthermore, to 15 provide an anvil having a surface particularly adapted for clenching the pegs when driven thereon.

The invention consists in an anvil adapted 20 to be attached to the horn of a pegging-machine in such a manner as to swivel thereon and having means attached thereto for guiding said anvil so that it shall maintain substantially the same relation to the edge of the shoe-sole which is being pegged upon it.

25 The invention again consists in an anvil, substantially as hereinbefore set forth, having the uppersurface adapted to the clenching of pegs driven thereon and having the face of said anvil adjacent to the advancing portion 30 of the shoe-sole beveled off to prevent roughing up or wrinkling of the inner sole of said shoe.

The invention consists, still further, in an anvil comprising a plate adapted to be attached to the horn of a pegging-machine in 35 such a manner as to swivel thereon, means for guiding said plate, and an arm pivoted to said plate and acting as a guide therefor.

The invention further consists in the combination and arrangement of parts set forth 40 in the following specification and particularly pointed out in the claims thereof.

Referring to the drawings, Figure 1 is a 45 plan view of my improved anvil. Fig. 2 is a longitudinal section taken on line 2 2, Fig. 1. Fig. 3 is a plan view similar to Fig. 1, showing my improved anvil in its relative position to a shoe, the sole of the shoe being broken away to show said anvil. Fig. 4 is a vertical section taken on line 4 4 of Fig. 3, showing a 50 portion of a shoe in connection with my im-

proved anvil, said anvil being shown supported upon the horn of a pegging-machine. Fig. 5 is an enlarged section through a portion of the anvil-plate on line 2 2, Fig. 1. 55

Like numerals refer to like parts throughout the several views of the drawings.

In the drawings, 8 is the anvil-plate, having a hole 9 extending through the same for the awl of the pegging-machine to pass into after 60 puncturing the sole of the shoe.

10 is a cylindrical flange formed upon the under side of said anvil-plate and having an annular groove 11 extending around the same. Said flange is formed to fit in a recess 65 12 in the top of the horn 13, so that the anvil-plate is free to swivel upon the horn 13.

At the left of the hole 9 are two grooves 14 15, separated from each other by a peg-dividing projection 16. On the other side of the hole 9 and diagonally opposite the grooves 14 15 the plate 8 is beveled or rounded off at 17, Figs. 2 and 5. The upper surface of the plate 8 is corrugated upon one of the longer sides thereof at 18. At the opposite end of 75 the plate from that having the beveled face 17 is an arm 19, pivoted between two ears 20 upon a pin 21. A torsional spiral spring 22 encircles the pin 21, one end thereof attached to the anvil-plate 8 and the other end to the 80 arm 19. A guide-roller 23 is journaled on a pin 24, fast to the outer end of the arm 19 and rotates in a slot 25 between two ears 26 upon said arm.

The operation of the device is as follows: 85 The shoe is placed upon the anvil in the usual manner and is fed in the direction of the arrow, Figs. 3 and 4, by an awl, which punctures the sole in line with the hole 9 in the anvil-plate 8. The peg is driven through 90 the hole previously punctured by the awl and immediately over the peg-dividing projection 16 in the upper face of the anvil-plate 8. It will be seen that the inner end of the peg will be divided and the two divided portions 95 thereof clenched by means of the peg-dividing projection and the grooves 14 and 15. Said peg-dividing projection is similar in construction and operation to that for which I have made application for Letters Patent of 100 the United States, Serial No. 30,378.

It will also be seen that by the construc-

tion of my improved anvil I am enabled to have a beveled end at 17, which is the end of the anvil first reached by the sole as it is being fed by the awl, and that said beveled end allows the inner sole to slip smoothly along over the surface of the anvil without wrinkling or crumpling the same, as is often the case in anvils having a flat upper surface throughout and having a square corner 10 which wrinkles the inner sole during the feeding operation. It is necessary that a portion of the upper surface of the anvil should be flat in order to have the pegs driven thereon, or it may be formed, as shown in the drawings, with a peg-dividing projection separating two grooves; but in any case there must be a surface upon which the peg can be driven and clenched. Hence an ordinary cylindrical anvil with no means for holding said 20 anvil in a fixed relation with reference to the edge of the sole of the shoe is necessarily flat over the entire upper surface, and the edge thereof forms a square corner with the periphery of said cylindrical anvil.

25 In my improved anvil the portion upon which the peg is clenched always remains to the left of the hole 9, Figs. 1 and 2, and the surface 17 upon the other side of the hole 9 diagonally opposite the grooves 14 15 can be 30 rounded or beveled off, as shown.

In order to hold the anvil in the relative position to the edge of the shoe-sole shown in Fig. 3, I provide the arm 19 and also make the anvil longer than it is wide, so that the 35 natural tendency of the shoe as it is fed in the direction of the arrow, Figs. 3 and 4, is to swing said anvil against the upper of the shoe and hold it in the position shown in Fig. 3. I also provide corrugations 18 along 40 one edge of said anvil at the side farthest away from the edge of the shoe-sole which is being pegged, the tendency being, as the shoe is fed, to push with more friction upon this roughened surface and swing the anvil 45 upon its swivel-flange 10 against the upper of the shoe along the edge of the sole. It will thus be seen that the beveled face 17 is always kept pointing in the direction opposite to that in which the shoe is feeding and 50 the portion of the anvil upon which the peg is driven and clenched is always kept to the left of the hole 9.

It is evident that the arm 19 may be dispensed with and the corrugations 18, the anvil-plate being made perfectly smooth, but with the pivotal point at one side of the center, between the two extreme ends of said plate, without departing from the spirit of my invention.

60 Having thus described my invention, what I claim, and desire to secure by Letters Patent, is—

1. An anvil for pegging-machines comprising a plate adapted to be attached to the horn 65 of a pegging-machine in such a manner as to

swivel thereon, and means for guiding said plate.

2. An anvil for pegging-machines comprising a plate adapted to be attached to the horn of a pegging-machine in such a manner as to 70 swivel thereon and an arm pivoted to said plate and acting as a guide therefor.

3. An anvil for pegging-machines comprising a plate adapted to be attached to the horn of a pegging-machine in such a manner as to 75 swivel thereon, an arm pivoted to said plate and acting as a guide therefor, and a spring attached to said arm and holding the same against the inner sole of a shoe resting on said horn.

4. An anvil for pegging-machines comprising a plate adapted to be attached to the horn of a pegging-machine in such a manner as to 80 swivel thereon, an arm pivoted to said plate, and a roller journaled thereon.

5. An anvil for pegging-machines comprising a plate adapted to be attached to the horn of a pegging-machine in such a manner as to 85 swivel thereon, an arm pivoted to said plate, a roller journaled thereon and acting as a 90 guide therefor, and a spring attached to said arm and holding the same against the inner sole of a shoe resting on said horn.

6. An anvil for pegging-machines comprising a plate adapted to be attached to the horn 95 of a pegging-machine in such a manner as to swivel thereon, a hole extending through said plate, two grooves in the upper surface of said plate at one side of said hole, said grooves separated from each other by a peg-dividing 100 projection and means for guiding said plate.

7. An anvil for pegging-machines comprising a plate adapted to be attached to the horn of a pegging-machine in such a manner as to 105 swivel thereon, one side of said plate beveled off at an angle with the top surface thereof, and means for guiding said plate.

8. An anvil for pegging-machines comprising a plate adapted to be attached to the horn of a pegging-machine in such a manner as to 110 swivel thereon, a hole extending through said plate, two grooves in the upper surface of said plate at one side of said hole, said grooves separated from each other by a peg-dividing 115 projection, a beveled surface on the side of said hole diagonally opposite said grooves, and means for guiding said plate.

9. An anvil for pegging-machines comprising a plate adapted to be attached to the horn of a pegging-machine in such a manner as to 120 swivel thereon, the point around which said anvil swivels being located eccentrically to the center of said plate.

In testimony whereof I have hereunto set my hand in presence of two subscribing witnesses.

ISAË FRÉCHETTE.
